[57] CLAIM

The ornamental design for a combined road courtesy light and control therefor, as shown and described.

DESCRIPTION

FIG. 1 is a front elevational view of the combined road courtesy light and control therefor showing my new design, the indicia being shown in broken lines on the light for illustrative purposes only;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view of the road courtesy light on a reduced scale, the fragmentary car being shown in broken lines for illustrative purposes only, and the control being omitted for convenience of illustration.

FIG. 1

FIG. 2

FIG. 3

FIG. 4

FIG. 5
